UNITED STATES PATENT OFFICE.

JOSEPH PERCY REMINGTON, OF PHILADELPHIA, PENNSYLVANIA, ASSIGNOR TO
REMININGTON MANUFACTURING COMPANY, OF PHILADELPHIA, PENNSYLVANIA, A
CORPORATION OF PENNSYLVANIA.

MOTIVE-FLUID-SUPPLY REGULATOR FOR INTERNAL-COMBUSTION ENGINES.

Application filed June 22, 1920. Serial No. 390,986.

To all whom it may concern:

Be it known that I, JOSEPH PERCY REMINGTON, a citizen of the United States, and a resident of Philadelphia, in the county of Philadelphia and State of Pennsylvania, United States of America, have invented certain new and useful Improvements in Motive-Fluid-Supply Regulators for Internal-Combustion Engines, whereof the following is a specification, reference being had to the accompanying drawing.

My invention relates to regulation of the motive fluid supply of internal combustion engines,—especially automobile engines,—my aim being to afford the engine an adequate supply of combustible mixture at all times and under all conditions, without danger of oversupply at any time. As applied to the engines of motor cars, my invention minimizes the ill effects of improper manipulation of the throttle by the driver of the car; improves the behavior of the car under variation of load, as in hill-climbing; eliminates "gas knocks" and other kindred or resultant troubles; and affords other advantages that will become apparent. I have hereinafter explained my invention, and described the best embodiment thereof at present known to me, with special reference to its employment on a gasoline automobile having the vacuum or suction system of fuel supply and equipped with a carbureter as its fuel feed device; it will be understood, however, that in its broader aspects the invention is not confined to the particular application and embodiment described, but can be otherwise carried out and employed.

The customary provision for control and regulation of the speed and running of an automobile internal combustion engine (aside from advancement and retardation of the spark, and from gear shift) is a throttle controlling the flow of combustible mixture to the engine and operated directly by the driver of the car, either by hand or by foot. However necessary and valuable as a means of general control over the supply of combustible mixture with reference to the desired running speed of the car, such a throttle affords but poor regulation of such supply with reference to the process of acceleration when the car is to be brought up to speed, or with reference to

the process of increasing the engine power 55 to enable the car to take a hill with minimum diminution of speed. This is primarily a consequence of peculiarities in the operating conditions of automobile engines,—although the lack of precision and delicacy inherent in arbitrary and empirical methods that leave everything to personal judgement and skill is also a factor.

As is well known, the cycle of operations in each cylinder of the ordinary automobile engine involves, first, a suction stroke, during which a charge of combustible mixture of air and gasoline from the fuel feed device or carbureter is drawn into the cylinder by the advancing piston; then a compression stroke, during which this combustible charge is compressed in the cylinder by the returning piston (being thereby heated more or less, according to the degree of compression); then a working stroke, 70 during which the compressed charge is ignited and burned, and the products of combustion are allowed to expand against the piston, so as to force it forward and drive the vehicle; and, finally, a scavenging stroke in which the returning piston expels the spent products of combustion from the cylinder so as to prepare it for the reception of a fresh combustible charge on the suction stroke of the next cycle. Only the 75 working stroke affords power for driving the vehicle; the other three strokes use up a certain amount of power, which is derived from the momentum of the vehicle due to previous working strokes and from the 80 working strokes of other cylinders. The greater part of this power consumption occurs, of course, on the compression stroke.

The degree of compression and the power required to effect it depend, of course, on 95 the amount of the charge drawn into the engine cylinder. This, in turn, depends on the pressure of the combustible mixture as actually drawn into the cylinder by the suction created by the moving piston; or, in other words, on the intensity of the suction or partial vacuum due to the failure of the fluid to flow in as fast as the piston moves. At fairly high running speeds of the car, 100 this suction intensity may be some 10 inches of mercury or more; while with the throttle wide open at very low speeds, it may drop to about $\frac{1}{2}$ inch or less. As would naturally

be expected, therefore, the greatest charges of combustible mixture are drawn into the engine cylinders at low speeds, so that the power required to effect compression is greatest when the momentum available for the purpose is least. This is most serious, of course, when the load on the engine is augmented by the vehicle's encountering a heavy grade, so that after each explosion the momentum must not only effect compression, but also keep the vehicle going on the upgrade until the next explosion occurs. Sudden wide opening of the throttle of a heavily loaded engine, tends, therefore, to slow it down excessively or to stall it, by reason of the extra burden of compression thereby superimposed. It also tends to produce severe laboring and racking of the engine. Under these same conditions of wide open throttle and low speed occurs, also, the phenomenon of so-called "gas knocks". Just what are the relations of such phenomena as gas knocks, racking and laboring, and high compression to one another and to the slowing down of the engine with wide open throttle and heavy load need not be here discussed at any length. There is reason to believe, however, that the burden of high compression imposed on the engine by sudden wide opening of the throttle under heavy load is not, directly and as a mere load, the entire cause of all these various phenomena, but that they are partly due to some effect of such concurrent throttle and load conditions on carburetion. This is confirmed by the observed coincidence of gas knocks with an overlean combustible mixture, as well as by fact that the operation of commercial forms of carburetor depends on the degree of vacuum around the gasoline nozzle or orifice of the carburetor. I have found that all these difficulties can be overcome, and the running of the engine greatly improved, by regulating the supply of combustible mixture to the engine according to the various principles and methods hereinafter explained with reference to the best and most highly organized modes of applying and carrying them out at present known to me. For the best results, the supply of combustible mixture should be increased progressively *pari passu* or proportionately with the concurrent increase of engine speed and acceleration of the car, and vice versa. I prefer to effect regulation upon this principle or method automatically (leaving to the driver and his arbitrarily operated throttle only a general control of the speed to be automatically established and maintained), since the driver who wants to increase or maintain his speed on a level or on a grade tends very strongly to throw the throttle wide open the moment the need arises, and it is very difficult or impossible for him to manipulate the

throttle with such delicacy of touch and nicety of judgment as to increase the available supply of motive fluid in proper proportion to the concurrently increasing car speed. Such automatic regulation of the supply of combustible mixture according to my method can be effected by opposing to the passage of the fluid mixture from the fuel feed device to the engine a resistance effective, at low speeds, to prevent the inflow of mixture from raising the pressure in the engine cylinders and intake to as high a level as at the air inlet of the fuel feed device,—or, in other words, which will maintain or insure a substantial partial vacuum in the engine intake under all running conditions. This need not interfere with the freest supply of combustible mixture to the engine at the higher speeds, or restrict the ultimate maximum speed and power of the engine, or prevent arbitrary control of the possible supply and speed at all times by means of the ordinary throttle. Nor, indeed, are the benefits of my invention confined to the very low speeds; on the contrary, it affords notable gains in speed and in load-carrying capacity at speeds materially higher than the low speeds entailed by the heaviest loads, though greatest at these latter speeds.

In the drawings, Fig. I is a conventional representation of an internal combustion engine equipped with means of regulation in accordance with my invention, and having a vacuum type of fuel supply system.

Fig. II is a sectional view through the intake passage or conduit leading from the fuel feed device or carburetor to the engine intake manifold, illustrating the application of a regulating device thereto in accordance with my invention.

Fig. III is a plan view of the regulating device, the intake conduit appearing in section at the line III—III in Fig. II.

Fig. IV is a sectional view through an engine intake illustrating a modified form and arrangement of regulating device.

Fig. V is a view of the regulating device proper and its mounting taken at right angles to Fig. IV, looking toward the left in that figure.

In Fig. I is represented an automobile engine 1 whose intake manifold 2 communicates with the fuel feed device or carburetor 3 through an intake passage or conduit comprehensively indicated by the reference numeral 4, the air inlet of the carburetor 3 being indicated at 5. Liquid fuel such as gasoline is supplied to the carburetor 3 from a supply tank 6 (here shown at a lower level than the carburetor) by means of a vacuum or suction system of any well-known or preferred type,—as, in particular, that disclosed in my application Serial No. 380,121, filed May 10, 1920. The fuel supply 1

system is here conventionally represented as comprising a float chamber 7 having a suction connection 8 to the engine intake 4, a delivery connection 9 to the carbureter 3, and a supply connection 10 to the gasoline tank 6. In the engine intake 4 is a device 11 for controlling and regulating the effective communication between the engine 1 and the carbureter 3 in accordance with my invention; also there is in the intake passage 4 the usual throttle 12 arbitrarily controlled by the automobile driver, and here shown as in a portion of the conduit 4 formed by a neck 13 on the carbureter 3.

5 Referring, now, to Figs. II and III, it will be seen that the regulator 11 acts automatically to diminish the effective communication between the engine 1 and the carbureter 3 with diminution of the velocity and flow of combustible mixture from the carbureter 3 to the engine cylinders, and vice-versa. As here constructed, this regulator 11 comprises a butterfly disc valve or closure member 20 slightly unbalanced in reference 25 to the influence of the fluid flowing past it, so that as this flow increases with increasing engine speed or acceleration the valve member 20 tends to open more and more, and vice-versa. This unbalanced tendency may 30 be produced by mounting the valve axis or shaft 21 off centre and arranging it so that in its most nearly closed position it extends diagonally or slantingly across the intake passage 4, as shown in Figs. II and III; 35 or by merely making one lobe of greater area than the other, as in Figs. IV and V, hereinafter described; or by any other well known or preferred means.

40 The opening tendency of the valve disc 20 under the influence of increasing speed of the fuel stream is yieldingly resisted by suitable loading of the valve, as by means of a counterweight comprising a pair of knurled lock-nuts 22, 22 screw-threaded and 45 adjustable lengthwise on a lever arm 23 fastened to the valve disc shaft 21. Complete closure of the valve disc 20 is prevented by engagement of a stop lug or shoulder 24 on the lever member 23 with a stop pin 25 50 projecting from a boss 26 on the conduit section 4 containing the valve disc 20; and derangement of the device by accidental throwing of the counterweight 22 over its dead centre is prevented by engagement of 55 another stop lug 27 on said lever member 23 with said stop pin 25. Fluttering of the valve disc 20 with the succession of individual suction impulses is prevented by its 60 inertia. The angular relation of the counterweight 22 to the valve disc 20 is such that its lever arm and effective valve diminish gradually as the valve opens, until in the full open position of the valve they are very slight. This progressive diminution of resistance to a relatively small value enables the

fluid stream to open the valve completely at high velocities, corresponding to high suction intensities above the valve; hence the valve does not sensibly affect the freest flow of combustible mixture to the engine 70 at high speeds of the latter.

The regulator 11 will preferably be so designed and so set (by appropriate proportioning and adjustment of its counterweight 22) as to remain in closed position, as shown, 75 at and below the minimum suction intensity for which the fuel supply system and the carbureter will operate satisfactorily, and to open fully (or substantially so) only by the time the engine attains a high speed. 80 To prevent knocking and meet all other requirements satisfactorily, it is usually best that with the hand throttle 12 wide open the valve 20 should just be starting to open when the suction has attained a substantial 85 but fairly small value, exceeding the normal, minimum value at the lowest speeds with the intake unobstructed by either the valve 20 or the throttle 12, such as about 2 inches 90 of mercury, and that at the ultimate maximum possible speed of the car on a level there should be no substantial difference in pressure between the two sides of the valve. When in its "closed" position shown, the 95 valve disk 20 should preferably afford no opening adjacent its larger upper lobe, and an opening adjacent its smaller lower lobe hardly less than equivalent to that afforded by the hand throttle when in any ordinary 100 starting position,—the extreme ordinary starting position of the hand throttle being, of course, about the "one-fourth open" one. The object of this calibration of the valve 20 is, of course, to avoid interference with 105 starting of the car in the usual manner; it will not be found inconsistent with the ability of the valve 20 to insure a minimum definite suction above it of about 2 inches of mercury under all running conditions 110 of the car, as above set forth.

Besides preventing overcharging of the engine cylinders and maintaining a partial vacuum in the engine intake under all running conditions, the regulator 11 tends, when partially closed, to deflect the stream of fluid through the intake and cause eddies therein that promote thorough intermingling of the air and gasoline, so as to produce a homogenous, uniform, combustible mixture 120 that is in itself favorable to good running and to increased power.

125 It will be seen, therefore, that the regulator 11 automatically varies the effective communication between the carbureter 3 and the engine 1 directly according to the flow of combustible mixture. This prevents an inexperienced driver from stalling his engine or unduly slowing his car by opening the throttle 12 too wide on starting 130 up a hill, so as to overcharge the cylinders

by admission of fuel at atmospheric pressure. Though the valve 20 may be placed at either side of the hand throttle 12, as found most convenient, its location between 5 the engine 1 and the carbureter 3 is quite important; for its action is thus that of a throttle regulating the quantity of combustible mixture reaching the engine, and not that of a "choke" regulating the richness 10 or leaness of the mixture,—as would be the case if it were located in the air inlet 5 of the carbureter. By tapping the intake suction connection 8 of a vacuum type fuel supply system into the intake passage 4 at 15 a point between the valve 20 and the engine, as shown, advantage can be taken of the fact that under all conditions a greater vacuum exists above than below the regulator 11, so as to utilize the intake vacuum 20 impulses to the best advantage. This is of greatest benefit, of course, in the case of a vacuum system not employing a reserve tank but capable of operating on low suction 25 intensities,—such as that described in my aforesaid application. In reference to this coaction of the regulator 11 with a vacuum type fuel feed system, the location of the valve 20 between the carbureter 3 and the engine rather than in the air inlet to the 30 carbureter is of special importance, since the resistance to air inflow to the intake offered by the throttling action of the loaded valve 20 results in the slight vacuua represented by engine suction impulses of low 35 intensity being satisfied in part by influx of liquid fuel from the tank 6 into the float chamber 7 of the supply system instead of being almost entirely satisfied by direct, free inflow of the body of air in the carbureter 3,—with consequent failure of the fuel supply system to function satisfactorily.

When an engine equipped with the regulator 11 is started, the valve 20 opens gradually and progressively in direct proportion 45 to the velocity of the fluid stream, which latter is dependent on the engine speed and, therefore, on its demonstrated capacity to carry the load. Any increase in the load slows the engine down, so that the lowered 50 velocity of the fuel stream allows the automatic throttle valve 20 to close partially, thus obviating the ill effects of a wide open throttle pointed out above. Any decrease 55 in load allows the engine to speed up before the automatic throttle can open. Thus the running condition or speed variation of the engine determines the concurrent automatic throttle opening in direct proportion and correspondence thereto, rather than the 60 throttle opening predetermining the running condition of the engine,—much less the mere arbitrary use of the hand throttle 12 by the driver. The latter may still, however, arbitrarily 65 close the throttle 12 or open it, so as either to limit the fluid stream and

its velocity to a value at which the automatic throttle 11 will remain closed, or to increase it to a point at which the automatic throttle 11 will begin to open as the engine picks up under the existing load. 70 The driver, therefore, controls the coming into action of the automatic throttle and the ultimate speed of the car, but has nothing to do with regulating its acceleration.

In Figs. IV and V is shown a modified 75 form of regulator specially suitable for insertion in horizontal intake passages of automobile engines already built or in use. This device comprises a plate 30 adapted to be inserted gasket-wise (with the usual accessory gaskets to secure fluid-tightness) between flanges 31 and 32 of sections of the intake passage,—which sections may be the horizontal carbureter neck 13 and the adjacent horizontal portion of the conduit section 35 in Fig. I. The circular opening in the plate 30 is surrounded by a flange 36 adapted to enter the internal bore of the conduit section 35, this flange affords a seat for a metal valve disc 37 pivoted loosely on 80 a shaft or mandrel 38 whose reduced ends enter holes in said flange. As shown the lower lobe of the disc 37 is the larger, so as to close off the lower half of the passage while the upper half affords an opening 85 above it, as in the case of Figs. II and III. As shown, the disc 37 is transversely slotted to afford a plurality of straps 39 which are oppositely bent to embrace the shaft 38, and carries a semi-circular sheet metal counterweight 40 flanged and riveted thereto at 41. Under the influence of gravity, therefore, the valve disc 37 naturally tends to occupy the 90 nearly vertically closed position shown, as determined by a stop projection 42 bent upward 95 from the flange 36. Overturning of the disc 37 in opening is prevented by engagement thereof, when about horizontal, with inward-bent stop projections 43 on the flange 36. For an ordinary car, the metal employed 100 may be sheet steel about $\frac{1}{16}$ " thick. The impact or pressure of fluid from the carbureter on the left-hand side of the disc 37 naturally tends to open it, owing to the greater area of the lower lobe, while the weight 40 105 tends to close it. Hence it opposes a yielding throttling resistance to the passage of the combustible mixture corresponding to that of the valve 20 in Figs. II and III, this 110 resistance approaching zero as the disc opens fully and the diminishing lower area of the counterweight 40 becomes very small. The intake suction connection 8 of the fuel supply system is, of course, between the valve disc 37 and the engine, just as in the device 115 shown in Figs. II and III.

Having thus described my invention I claim:

1. The combination with the intake of an internal combustion engine, of a throttle 130

therein yieldingly resistant and responsive to the flow of fluid therethrough for automatically augmenting and diminishing the supply of combustible mixture *pari passu* with concurrent variation in engine suction, so as to regulate the acceleration and power in reference to the load; said throttle comprising a butterfly valve having one lobe reduced to accommodate normal starting conditions but unbalanced in reference to the influence of the fluid flowing past it, and means for producing a turning moment tending to close the valve which diminishes in influence as the valve approaches full open position.

2. The combination with the intake of an internal combustion engine, of a throttle therein yieldingly resistant and responsive to the flow of fluid therethrough for automatically augmenting and diminishing the supply of combustible mixture *pari passu* with concurrent variation in engine suction so as to regulate the acceleration and power in reference to the load; said throttle comprising a butterfly valve having the lower lobe arcuately reduced to accommodate normal starting conditions but unbalanced in reference to the influence of the fluid flowing past it, means for producing a turning moment tending to close the valve comprising a lever arm with adjustable counterweight extending at a slight angle to the plane of the valve, and means functional to limit said turning moment.

3. The combination with the intake of an internal combustion engine of a throttle valve therein, yieldingly resistant and responsive to the flow of fluid therethrough, for automatically augmenting and diminishing the supply of combustible mixture with concurrent variation in engine suction so as to regulate the acceleration and power with reference to the load, said throttle valve affording an opening accommodating normal starting conditions, and gravity operable means associated with said throttle for urging the throttle to closed position but adapted to progressively yield its impulse to subsidence in proportion to the degree of movement of the throttle as the latter moves to open position.

4. The combination with the intake of an internal combustion engine, of a butterfly throttle therein having a reduced lobe at one side of its axis, yieldingly resistant and responsive to the flow of fluid therethrough for automatically augmenting and diminishing the supply of combustible mixture with concurrent variation in engine suction, so as to regulate the acceleration and power with reference to the load, an arm movable with the throttle having movement limiting stops and extending horizontally when the latter is closed, and a weight adjustably carried by the arm, whereby said arm is carried toward a vertical position as the throttle moves to open position so as to result in a corresponding decrease in gravitational effect upon the throttle tending to close the latter.

5. An acceleration and power regulator for an automobile internal combustion engine comprising, in combination with the intake of such engine, unbalanced gravity-fall butterfly-valve having a reduced lobe at one side of its axis responsive to the velocity of flow therethrough for automatically diminishing or increasing the effective communication between the engine and its fuel feed device *pari passu* with variation of the engine speed.

6. The combination with the intake of an internal combustion engine, of an unbalanced gravity-fall butterfly throttle therein having a reduced lobe at one side of its axis yieldingly resistant and responsive to the flow of fluid therethrough for automatically augmenting and diminishing the supply of combustible mixture *pari passu* with concurrent acceleration or slowing up of the engine, so as to regulate the acceleration and power of the latter in reference to the load; and an arbitrarily operated throttle also controlling the flow of combustible mixture to the engine, so as to control the action of the aforesaid automatically acting unbalanced throttle and the possible speed of the engine.

In testimony whereof, I have hereunto signed my name at Philadelphia, Pennsylvania, this 17th day of June 1920.

JOSEPH PERCY REMINGTON.
